United States Patent

Des. 234,316
Patented Feb. 11, 1975

234,316

PHONOGRAPH

Robert F. Mansfield, Tokyo, Japan, assignor to
Capehart Corporation, New York, N.Y.

Filed Sept. 18, 1972, Ser. No. 290,219

Term of patent 14 years

Int. Cl. D14—01

U.S. Cl. D56—4 R

FIG. 1

FIG. 2

FIG. 3

FIG. 5

FIG. 6

FIG. 1 is a front, top and right side perspective view of a phonograph showing my new design;

FIG. 2 is a front elevational view;

FIG. 3 is a right side elevational view;

FIG. 4 is a left side elevational view;

FIG. 5 is a top plan view; and

FIG. 6 is a bottom plan view.

The rear of the phonograph is plain and unornamented.

Portions of the phonograph that would be seen through the transparent cover in FIGS. 3 and 4 have been omitted for convenience of illustration.

I claim:

The ornamental design for a phonograph, as shown and described.
